CLAIM

The ornamental design for a pumping unit for oil wells
or the like, as shown and described.

DESCRIPTION

FIG. 1 is a side elevational view of a pumping unit for
oil wells or the like showing our new design, the oppo-
site side being substantially similar in appearance;

FIG. 2 is a front elevational view thereof;

FIG. 3 is a top, front and side perspective view thereof;
and

FIG. 4 is a rear elevational view thereof.

FIG. 2

FIG. 3
